(57) **CLAIM**

The ornamental design for a filament spool container, as shown and described.

DESCRIPTION

FIG. 1 is a top front perspective view of a first embodiment of a filament spool container;

FIG. 2 is a bottom front perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is a top front perspective view of a second embodiment thereof; the second embodiment being a reciprocal of the first embodiment;

FIG. 10 is a bottom front perspective view thereof;

FIG. 11 is a top view thereof;

FIG. 12 is a bottom view thereof;

FIG. 13 is a front view thereof;

FIG. 14 is a rear view thereof;

FIG. 15 is a left side view thereof; and,

FIG. 16 is a right side view thereof.

Features illustrated with dashed lines are not considered features of the invention being claimed, but rather illustrate an exemplary environment for the claimed features illustrated with solid lines.
